GUN RACK

Harold W. Jennings, Berkeley, Calif.

Application July 6, 1936, Serial No. 88,926

1 Claim. (Cl. 211—64)

This invention relates to racks in which groups of rifles, or arms of a like nature, may be irreversibly stored.

It is an object of the invention to provide a rack, of the character described, which is constructed of light weight material, yet which is sufficiently rugged to resist any attempts to forcibly release the arms stored therein.

A further object of the invention is to provide novel means for simultaneously securing, or releasing, arms in, or from, such a rack.

Still another object of the invention is to provide a novel construction for the sockets in which the respective ends of the rifle, or other arm to be stored in the rack, are secured.

The invention possesses other objects and features of value, some of which, together with the foregoing, will be specifically set forth in the specification hereunto annexed. It is to be understood that the invention herein disclosed is not to be limited to the particular species thereof shown and described, as various other embodiments thereof may be employed within the scope of the appended claim.

25 Referring to the drawing:

Figure 1 is a front elevational view of the gun storage rack of my invention.

Figure 2 is a side elevational view of the structure illustrated in Figure 1.

30 Figure 3 is a perspective view, of a portion of the rack, showing the construction of the sockets for enclosing the gun butts.

Figure 4 is a perspective view, of an upper portion of the rack, showing the construction of the 35 sockets for enclosing the gun muzzles.

In detail, the rack is made up of standard and 40 specially formed structural steel bars and comprises a pair of spaced rear standards 5, which may be fastened, by angle clips 6 secured to the respective ends thereof, to the ceiling and floor of a room. Disposed in front of, and spaced from, the rear standards 5 is a pair of front legs 7, secured to the rear standards by means of tie plates 8 and provided, at their lower ends, with 45 clips 9 by means of which the legs may be secured to the floor of the room. Intermediate front and rear legs 10 are provided secured together by means of tie plates 11 and provided at their lower ends with floor attachment clips 12.

50 The intermediate legs are supported by crossed bracing bars 13 which are secured, respectively, at the point of intersection thereof, to the intermediate legs and at their ends to the rear standards 5 and the front legs 7. It will of course be understood that as many of the legs 10 as de-

sired may be provided, this number depending on the length of the space between the standards 5.

Secured to the upper ends of the members 7 and 10, and the upper edge of each upper tie plate 8, is a shelf 14 having a portion thereof, along its rear edge, turned upwardly to provide a flange 15, which is secured to each standard 5, and a portion thereof, along its front edge, turned downwardly to provide a flange 16 which is secured to the front face of the front legs 7 and 10. Disposed in spaced relation on the shelf 14 is a plurality of U-shaped sheet metal spacers 17 each provided with oppositely directed flanges 18 which are secured, preferably by welding, to 15 the shelf flange 15, and at each end of the group of spacers is provided an angle clip 19 which is welded to the shelf 14 and the flange 15. It will be seen that each spacer 17 provides between it and an adjoining spacer, a socket 20 open at 20 its forward end and adapted to receive the end of the gun stock shown by the dotted lines 21 of Figure 3.

Means is provided for locking, against removal through the open end of each socket 20, the guns 25 placed in the sockets. Pivotally secured to the front face of the flange 16, by hinges 22, is an angle bar 23, which may be moved from the position shown in the left-hand portion of Figure 3 wherein the front of each socket 20 is open, there- 30 by permitting the gun stocks 21 to be moved forwardly out of the sockets, to the position in which it is shown in the right-hand portion of Figure 3, wherein one flange of the angle bar lies across and closes the front of each socket 20 to prevent 35 the displacement of the gun stocks from the sockets. To maintain the angle bar in this latter position, wherein the sockets are closed, the upright flange of the former is provided with one or more apertures 24 through which passes a lug 40 25, which is suitably secured to the front of one of the spacers 17, or to any other convenient portion of the rack frame, and provided with an aperture 26 in which the U-shaped shackle of a padlock may be secured.

45 Means is provided for preventing upward movement of the gun stocks 21 locked in the sockets 20. Secured, at its opposite ends, to the front face of each of the standards 5, is an angle bar 27 to which is welded, or otherwise secured in vertical alignment with each socket 20, a plurality of U-shaped plates 28 which provide pockets 29, which receive the end of the gun barrel, shown by the dotted lines 30 of Figure 4. The upper end of each pocket is closed by the overlying flange of the 50 55

angle bar 21 so as to preclude upward movement of the gun barrel relative to the pocket. This will, of course, prevent the gun stock 24 from being lifted vertically out of its socket 20.

5 In conclusion, the gun storage rack just described, although constructed of thin gage metal members, is possessed of a high degree of strength and rigidity which enables it to withstand attempts to forcibly remove the arms stored there-
10 in; reduces the amount of extra weight which floors of armories and like places where arms are stored were required to support due to the heavy construction of such racks in general use; and provides, in the locking bar 23, a simple device
15 for simultaneously and quickly opening or closing all of the sockets in which the arms are locked.

I claim:

20 A gun storage rack comprising pairs of spaced, vertically disposed, frame members, a bar secured at its ends to a pair of said frame members adjacent the upper ends thereof, a plurality of members secured to a vertical surface of said bar to

provide along said bar a row of spaced, axially vertical, sockets into which the end of the barrels of a plurality of guns may be placed, a flange extending from an edge of said bar and overlying the upper end of each of said sockets, a 5 horizontal shelf secured at its respective ends to said frame members in spaced relation to said bar, said shelf having a flange rising from one longitudinal edge thereof, a plurality of spaced elements secured to said shelf and to said flange 10 thereof to provide on said shelf a row of recesses having an open top and end and vertically aligned with the sockets on said bar, said recesses each being adapted to receive the stock of a gun, a bar hingedly secured to the longitudinal edge of 15 said shelf opposite said shelf flange, said bar being movable into a position to close the open end of each of said recesses to enclose the stocks of said guns therein, and means for securing said bar in said position.

20

HAROLD W. JENNINGS.
